JOHN MARTINO, JACOB BEESLEY, AND JOHN CURRIE, OF PHILADELPHIA,
PENNSYLVANIA, ASSIGNORS TO SMITH, WELLS & CO., OF SAME PLACE.

Design No. 2,611, dated April 9, 1867.

DESIGN FOR A COOK'S STOVE.

The Schedule referred to in these Letters Patent and making part of the same.

TO ALL WHOM IT MAY CONCERN:

Be it known that we, JOHN MARTINO, JACOB BEESLEY, and JOHN CURRIE, of Philadelphia, county of Philadelphia, and State of Pennsylvania, have invented or produced a new and original Design for a Cook Stove, termed the "Regulator No. 7;" and we do hereby declare that the accompanying drawing, and the following explanation thereof, form a full, clear, and exact description of the said design.

Figure 1 is a perspective view of the stove; and

Figure 2, a view of the back plate of the same.

The side plate A of the stove has one large door and two smaller doors, each door having a central ornament of the character clearly shown in the drawing, as well as the foliated ornaments near the corners. Below the doors is a long ornamental panel. The front plate B has two doors having ornaments of a character similar to those on the doors of the side plate, and has foliated ornaments on each side of the doors. The form and ornamentation of the back plate C and other plates of the stove, as well as of the legs a, are too clearly shown in the drawing to need description.

We claim the design for a cook stove, substantially as represented in and by the accompanying drawing.
In testimony whereof we have signed our name to this specification in the presence of two subscribing witnesses.

JOHN MARTINO,
JACOB BEESLEY,
JOHN CURRIE.
